UNITED STATES PATENT OFFICE.

ANDERSON B. COSBY, OF RICHMOND, VIRGINIA.

CHURN-COVER.

SPECIFICATION forming part of Letters Patent No. 377,710, dated February 7, 1888.

Application filed December 21, 1887. Serial No. 258,625. (No model.)

To all whom it may concern:

Be it known that I, ANDERSON B. COSBY, of Richmond, in the county of Henrico and State of Virginia, have invented a new and useful Improvement in Churn-Covers, of which the following is a specification.

My invention relates to that class of churn-covers in which a marginal ring with hook-shaped lugs is fixed to the upper edge of the churn-body, and a disk-shaped cover is provided with a set of radial levers projecting beyond the edge of the disk for engagement with said lugs, the said levers being arranged to work in a vertical plane (and simultaneously) by the same cam or screw plate at the center, so as to tighten under the lugs, and thus hold the cover firmly down.

My invention consists in the peculiar construction of a screw-cup, in combination with its inclosing-shell and the levers, as will be hereinafter fully described.

Figure 1 is a plan view. Fig. 2 is a section through *x x*. Fig. 3 is an enlarged section through *y y*; Fig. 4, an enlarged section through *z z*, and Fig. 5 a detail in perspective of one of the levers.

In the drawings, A represents the marginal metal ring, which is screwed or otherwise fastened to the top edge of the churn-body. This ring has four upwardly-projecting hook-shaped lugs, *a*, cast upon it, and has also its inner edge slightly raised to form a bead, *b*, upon which the wooden cover B fits and makes a tight joint.

C is another marginal ring, which is fastened to the edge of the cover B, and is provided with four fulcrum-seats, *c*, which are in the nature of lugs, with inverted-T-shaped or undercut slots.

D are the levers, which are four in number and are arranged radially. These levers at their fulcrum-point have ribs *d d* on their sides, which fit beneath the overhanging edges of the fulcrum-seats and prevent the levers from being lifted out, but at the same time allow the levers to be slipped endwise into the fulcrum-seats and to have therein a slight oscillatory motion about the fulcrum-point. The inner ends of the levers extend into vertical slots *e* in a retaining-shell, E, which is fastened to the center of the cover and retains the actuating screw-cup. F is this screw-cup, which is closed at the top and open at its bottom end, and provided on its outer periphery with deep screw-threads *f*,

which receive the inner ends of the levers, which latter have cross-heads *g* on them, to prevent the levers from passing endwise out through the slots *e* in the encompassing-shell. The screw-cup is retained in the shell by a shoulder-bolt, G, which forms an axis for the screw-cup to turn upon. The shoulder *h* of the bolt forms a bearing, by which the nut *i* on the lower side of the cover is made to clamp the bolt without bringing any cramping strain on the screw-cup, allowing the latter perfect freedom of motion. This screw-cup has four independent parallel threads—one for each lever—the object in multiplying the threads being to bring all the inner ends of the levers in the same horizontal plane. To the upper portion of the screw-cup is attached or cast one or more handles or lugs, *k*, by which it is turned.

To operate the cover, it is applied to the ring on the churn and the cover slightly turned, so as to bring the outer ends of the levers beneath the hooks on the churn-body. The screw-cup is now turned about its vertical axis, and its thread causes the inner ends of the lever to be simultaneously depressed and the outer ends beneath the hooks to be raised, which causes the cover to be tightly pressed down upon the churn at four equidistant points.

I do not broadly claim the levers and an adjusting cam or screw at the center for operating them; but

What I claim is—

1. The combination, with the cover bearing a ring with undercut fulcrum-seats *c*, of the levers *D*, having ribs *d d* and cross-head *g*, the vertically-slotted shell *E*, and the screw-cup *F*, arranged about a vertical axis within the shell and having peripheral threads adapted to receive the cross-heads of the levers, substantially as and for the purpose described.

2. The combination of the marginal ring A with hook-shaped lugs *a* and bead *b*, the cover with marginal ring C, having undercut fulcrum-slots, the levers D, with ribs *d* and cross-head *g*, the vertically-slotted retaining-shell E, the screw-cup F, and the axial shoulder-bolt G, substantially as and for the purpose described.

ANDERSON B. COSBY.
